UNITED STATES PATENT OFFICE

123,022

DESIGN FOR A CHENILLE ROBE

Charles Shapiro, New York, N. Y.

Application August 22, 1940, Serial No. 94,546

Term of patent 3½ years

To all whom it may concern:

Be it known that I, Charles Shapiro, a citizen of the United States, residing in New York, New York, have invented a new, original, and ornamental Design for a Chenille Robe, of which the following is a specification, reference being had to the accompanying drawings forming a part thereof.

Fig. 2 is a back view thereof.

I claim:

The ornamental design for a chenille robe, as shown.

CHARLES SHAPIRO.
